UNITED STATES PATENT OFFICE.

JEAN F. WEBB, SR., OF NEW YORK, N. Y.

PARACHUTE ATTACHMENT FOR FLYING-MACHINES.

1,314,446.

Specification of Letters Patent. Patented Aug. 26, 1919.

Application filed July 2, 1917, Serial No. 178,230. Renewed October 23, 1918. Serial No. 259,458.

To all whom it may concern:

Be it known that I, JEAN F. WEBB, Sr., residing at New York, in the county of New York and State of New York, have invented 5 certain new and useful Improvements in Parachute Attachment for Flying-Machines, of which the following is a specification.

The object of this invention is to provide a parachute attachment for aeroplanes that 10 is so small and compact when reeled in, and in place ready for instant action, that it offers no resistance to the air in flying, and is practically invisible; yet when unreeled and expanded it has such an enormous sus- 15 taining power that it will sustain, not only the aviator, but the weight of the aeroplane also.

It is preferably attached to, or built into the fuselage of an aeroplane, just behind the 20 seat of the aviator, and is so designed that in time of danger it can be instantly thrown into the air and automatically unreeled and expanded.

Other objects are to provide means where- 25 by the aviator may climb up into the first parachute to a place of safety, should occasion make it desirable, as for instance, in the event of the machine catching fire, and also to provide means whereby the aviator, 30 having reached the place of safety, may detach the aeroplane from the parachute and himself make a safe landing.

Generically the foregoing objects are ob- 35 tained by building a long narrow box of light material in the fuselage of the machine, just back of the aviator's seat, and as near the center of gravity of the machine as possible, the box being provided with quick opening instrumentalities; in this box is 40 located a reel on which collapsible para- chutes are wound when not in use, the several parachutes being serially secured to a strong spring cable of flexible steel wire, or other suitable material, an automatically 45 opening air anchor or "umbrella-like" de- vice being secured to the outer end of the cable, while the inner end is made fast to the reel, the cable being knotted, if desired, at intervals from the reel upwardly a sufficient 50 distance to enable the aviator to climb to a place of safety. A detaching device may be provided whereby the aviator may then re- lease the parachute from the machine.

More subordinately the invention is an 55 improvement on that disclosed in my Patent No. 1,011,683, issued December 12, 1911.

In its more detailed nature, the invention includes those novel details of construction, combination and arrangement of parts, all of which will be first fully described, then be 60 specifically pointed out in the appended claims, and illustrated in the accompanying drawings, in which:—

Figure 1 is a perspective view illustrating the invention in use. 65

Fig. 2 is a side elevation of the same.

Fig. 3 is a view illustrating how the para- chutes may be laid out for reeling on the reel.

Fig. 4 is an enlarged vertical longitudi- 70 nal section of the box showing the para- chutes unreeling from the reel.

Fig. 5 is a side elevation of the box, in the normal position, parts being broken away to show the relative positions of the reeled 75 up parachutes and the air anchor.

Fig. 6 is a cross section on the line 6—6 of Fig. 5.

Fig. 7 is a detail view showing a releasing device that may be employed. 80

Fig. 8 is a side view, parts being broken away illustrating a modification of the in- vention.

Fig. 9 is a side elevation illustrating an- 85 other modification of the invention.

In the drawings, in which like letters and numerals of reference indicate like parts in all of the figures, 1 is the flying machine whose fuselage 2 is provided with a light long box 3 of aluminum, or other suitable 90 material, which is located just back of the aviator's seat and includes bearing supports 4 for a rod 5 which is secured by nuts 6 pinned at 7 against turning off. The rod 5 sustains the reel, which consists of the tu- 95 bular portion 19 and the heads 20, the heads 20 having recesses 21 in which ball bearings 22, of any approved design, are retained by retaining caps or plates 23 so that the bear- 100 ings may remain in place when the reel is removed for winding up the parachutes, as will be later explained.

26 is the suspension cable which is wound around the reel as at 25 and secured to the eye 24 that is suitably fastened to the reel 105 as a permanent part.

27 indicates "knots" or enlargements in the cable 26 which are located at intervals from the reel upwardly to the first para- chute 29, it being understood that a plural- 11 ity of parachutes 29 are preferably used and arranged *seriatim* on the cable 26.

28 is a releasable connector which, when released, will permit the aeroplane to drop.

The parachutes 29 are of any approved construction, either of the design shown in 5 the accompanying drawings, or that shown in my patent above referred to, or any other suitable design, but when constructed as shown in the drawings, they are preferably provided with small area air escapes 32 at 10 the top and larger air entrances 31 at the bottom.

The bottom or mouth of the parachute is guyed by suitable guy cables 30, to the suspension cable 26.

15 18 designates an air anchor which may be of any approved construction, but preferably such as shown in my patent hereinbefore referred to, the anchor consisting of a self-opening "umbrella-like" device that 20 functions to catch the air and drag out the collapsible parachute parts into position to be opened as the machine drops.

The releasing device 28 may be of any approved construction, such as shown in 25 Fig. 7, in which a lever 33 is fulcrumed at 34 to the channeled member 28 and held in position by a pin 35, the lever 33 being designed to be self-opening when the pin 35 is withdrawn, a ring 36 serving to connect 30 the lower section of the cable 26 with the lever 33, while the upper section of the cable 26 is connected at 37 to the device 28, as illustrated.

The box 3 is provided with lids 8 that are 35 hinged by self-opening hinges 9 to the box, the lids 8 having their adjacent edges overlapping (see Fig. 6) when closed and they are held closed by the latch dog 11 on the lever 12 that is secured to the flap 14, which 40 is hinged to the front wall of the box, so that it may be thrown open, as shown in Fig. 4, to release the lids and permit the air anchor to open out. The hinge flap 14 is provided with a socket 16 in which the shank 45 17 of the air anchor is fastened to hold the anchor down when the box is closed.

The dog 11 is designed to engage a holding latch 10 on the lids and is preferably held in such engagement by spring pressure, 50 as for instance, by a stout spring 13, or any other suitable way.

In practice, the parts are normally positioned as shown in Fig. 5, but should occasion require the release of the safety appliance, the aviator simply pulls on the lever 55 12 to throw it into position, shown in full lines in Fig. 4, whereupon the lids of the box will open out, the air anchor 18 will spring to its open position, catch the air, 60 release itself from the socket 16 and unreel the parachutes. As the parachutes unreel, the air entering the same through the entrances 31 will expand the parachutes, which will then perform their desired 65 functions.

Should the machine catch on fire, the aviator may climb to a place of safety above the releasing device 28 and by withdrawing the pin 35 he may release the air ship which may be permitted to fall and the aviator be lowered gradually and safely by the 70 parachute device.

Numerous modifications and adaptations of the invention may be readily made, as will be manifest to those skilled in the art, 75 and I do not wish to limit myself to the structure shown and described, although the same is the preferable form, beyond what may be necessary by the state of the prior art and the scope of the appended claims. 80

It should be understood that the fabric of the parachute and the air anchor is preferably fire-proofed by impregnation with a suitable fire-proofing compound so that the 85 parachutes will not take fire in the event that the aeroplane catches on fire.

Should the machine not be detached from the parachutes, after the ground has been reached, the parachutes and air anchor may be replaced into the box by removing the 90 reel (and this is done by taking out the rod on which the reel turns) and laying the parts down on the ground, as shown in Fig. 3, with the parachute members collapsed, and they may then be rolled upon the reel, 95 after which the reel may be replaced in the box and the air anchor closed and placed in its position also.

In the modification shown in Fig. 8, the 100 spool is dispensed with and the parachute members and air anchor are folded longitudinally in the chamber 3 formed in the fuselage, while in the modification shown in Fig. 9, the spool 20 is located transversely in the chamber 3 in the fuselage so as to 105 facilitate the unwinding of the parachute elements and prevent any possible binding of the same at the rear end of the chamber.

From the foregoing description, taken in connection with the accompanying drawings, it is thought the complete construction, 110 operation and advantages of my invention will be readily understood by those skilled in the art.

What I claim is:

1. The combination with an aeroplane having a fuselage, of a box built into the fuselage, a self-opening cover for said box, means for releasing said cover, a reel in 120 said box, a parachute device having a cable wound on said reel and connected to sustain the machine when the parachute is released, an air anchor connected to said parachute device and normally located in said box, and means for releasing said air 125 anchor when said cover is opened.

2. The combination with an aeroplane having a fuselage, of a box built into the fuselage, a self-opening cover for said box, releasable means for holding said cover 130

- closed, said releasable means including a lever element having a socket, a reel in said box, a parachute device having a cable wound on said reel and connected to sustain said machine when said parachute device is released, an air anchor connected to said device and normally located in said box, said air anchor having a shank to enter said socket and adapted to be released when said cover is opened.
3. The combination with an aerial navigating machine having a fuselage, a reel located within the confines of the fuselage, a parachute device having a sustaining cable connected to said reel, said device being windable on said reel, an air anchor connected to said parachute device and adapted to be located within the confines of the fuselage, and means for releasing said anchor from the fuselage to unreel the parachute device.
4. The combination with an aerial navigating machine having a fuselage, a reel located within the confines of the fuselage, a parachute device having a sustaining cable connected to said reel, said device being windable on said reel, an air anchor connected to said parachute device and adapted to be located within the confines of the fuselage, means for releasing said anchor from the fuselage to unreel the parachute device, said means comprising a lever device having a socket, said anchor having a shank to enter said socket, means holding said lever device to restrain said anchor, said lever device adapted to be moved by the aviator to release said anchor, said cable having "knots" at intervals from the machine, substantially as shown and for the purposes described.
5. The combination with an aeroplane having a fuselage, of a box built into the fuselage, a self-opening cover for said box, means for releasing said cover, a reel in said box, a parachute device having a cable wound on said reel and connected to sustain the machine when the parachute is released, an air anchor connected to said parachute device and normally located in said box, means for releasing said air anchor when said cover is opened, said cable having "knots" at intervals from the machine.
6. The combination with an aeroplane having a fuselage, of a box built into the fuselage, a self-opening cover for said box, releasable means for holding said cover closed, said releasable means including a lever element having a socket, a reel in said box, a parachute device having a cable wound on said reel and connected to sustain said machine when said parachute device is released, an air anchor connected to said device and normally located in said box, said air anchor having a shank to enter said socket, and adapted to be released when said cover is opened, said cable having "knots" at intervals from the machine.
7. The combination with an aerial navigating machine having a fuselage, a reel located within the confines of the fuselage, a parachute device having a sustaining cable connected to said reel, said device being windable on said reel, an air anchor connected to said parachute device and adapted to be located within the confines of the fuselage, means for releasing said anchor from the fuselage to unreel the parachute device, said cable having "knots" at intervals from the machine.
8. The combination with an aerial navigating machine having a fuselage, a reel located within the confines of the fuselage, a parachute device having a sustaining cable connected to said reel, said cable being windable on said reel, an air anchor connected to said parachute device and adapted to be located within the confines of the fuselage, means for releasing said anchor from the fuselage to unreel the parachute device, said means comprising a lever device having a socket, said anchor including a shank to enter said socket, means holding said lever device to restrain said anchor, said lever device adapted to be moved by the aviator to release said anchor, said cable having "knots" at intervals from the machine, substantially as shown and for the purposes described.
9. The combination with an aeroplane having a fuselage, of a box built into the fuselage, a self-opening cover for said box, means for releasing said cover, a reel in said box, a parachute device having a cable wound on said reel and connected to sustain the machine when the parachute is released, an air anchor connected to said parachute device and normally located in said box, means for releasing said air anchor when said cover is opened, said cable having "knots" at intervals from the machine, and a releasable connection in said cable whereby the aviator can disconnect the parachute from the machine after climbing to a place of safety.
10. The combination with an aeroplane having a fuselage, of a box built into the fuselage, a self-opening cover for said box, releasable means for holding said cover closed, said releasable means including a lever element having a socket, a reel in said box, a parachute device having a cable wound on said reel and connected to sustain said machine when said parachute device is released, an air anchor connected to said device and normally located in said box, said air anchor having a shank to enter said socket, and adapted to be released when said cover is opened, said cable having "knots" at intervals from the machine, and a releasable connection in said cable whereby the aviator can disconnect the parachute from the machine after climbing to a place of safety.

11. The combination with an aerial navigating machine having a fuselage, a reel located within the confines of the fuselage, a parachute device having a sustaining cable 5 connected to said reel, said device being windable on said reel, an air anchor connected to said parachute device and adapted to be located within the confines of the fuselage, means for releasing said anchor from 10 the fuselage to unreel the parachute device, said cable having "knots" at intervals from the machine, and a releasable connection in said cable whereby the aviator can disconnect the parachute from the machine after 15 climbing to a place of safety.

12. The combination with an aerial navigating machine having a fuselage, a reel located within the confines of the fuselage, a parachute device having a sustaining cable 20 connected to said reel, said cable being windable on said reel, an air anchor connected to said parachute device and adapted to be located within the confines of the fuselage, means for releasing said anchor from the 25 fuselage to unreel the parachute device, said means comprising a lever device having a socket, said anchor having a shank to enter said socket, means holding said lever device to restrain said anchor, said lever device 30 adapted to be moved by the aviator to release said anchor, said cable having "knots" at intervals from the machine, and a releasable connection in said cable whereby the aviator can disconnect the parachute from 35 the machine after climbing to a place of safety.

13. The combination with an aeroplane

having a fuselage, of a chamber in the fuselage, and a self-opening cover for said chamber, a hinged body having a socket member 40 and a latch device carried by said hinged body for holding said cover closed with said socket member projected into the chamber, a parachute device having a cable secured within the chamber and a plurality of parachute members connected with said cable and adapted to be normally located within said chamber, an air anchor connected to said cable and having a shank held in said socket member, all being arranged whereby 50 as said latch device is operated to release said cover said hinge member will move on its hinged axis to raise said air anchor out of said chamber, substantially as shown and described.

14. The combination with an aeroplane having a fuselage provided with a chamber, a self-opening cover for said chamber, a lever actuated latch device for holding said cover closed, a plurality of serially arranged 60 parachute members connected on a cable which is secured to the fuselage at one end, an air anchor connected at the other end of said cable, said parachute members and said air anchor adapted to be located within said 65 chamber with the cover closed under normal conditions, means for holding said air anchor within the chamber, said means connected with said lever actuated device for lifting said air anchor out of said chamber 70 as said cover is released, substantially as shown and described.

JEAN F. WEBB, Sr.
